ORNAMENTED SILK LAMP SHADE

Application filed March 25, 1930. Serial No. 438,719.

This invention relates to ornamental lampshades, and more particularly to a lampshade made from a silk fabric having one surface thereof provided with a coat of scraped 5 crackled lacquer having a translucent dull finish, and closely simulating the appearance of leather.

One object of this invention is to provide an ornamental lacquered silk lampshade 10 which may be cheaply and easily manufactured, which will not deteriorate in storage, and which will be capable of withstanding extreme heat, cold, and moist air conditions.

With these and other objects in view, there 15 has been illustrated on the accompanying drawing one form in which the invention may be conveniently embodied in practice.

In the drawing:

Fig. 1 represents an elevation of a typical 20 ornamental lamp, having a shade embodying the invention.

Fig. 2 is a fragmentary surface view of a portion of the silk fabric from which the lampshade is constructed.

Fig. 3 is a sectional edge view of said 25 fabric.

Referring now to the drawing in which like reference numerals denote corresponding parts throughout the several views, the 30 numeral 10 indicates a lamp base for supporting a lampshade 11 which is completely covered with a sheet of silk fabric 12, which may be plain, colored, or ornamented as desired.

In order to produce a crackled or imitation leather appearance upon the lampshade 35 in accordance with the present invention, a thin foundation coating 13 of pyroxylin lacquer, containing castor oil as a plasticizer, will first be applied to the inside surface of the silk fabric 12, preferably by means of a compressed air spray gun, not shown, the outside surface of the silk fabric being left uncoated. After the foundation coat 13 has 40 been allowed to dry three or four hours, a second coat of lacquer of similar composition will be applied in the same manner and allowed to dry for about the same period of time.

The next step of the process is to apply a

coating of so-called quick-drying "crackle" lacquer having the property of forming a leather-like mottled surface as the solvent evaporates therefrom. The coat of "crackle" lacquer will be allowed to dry for ten or 55 fifteen minutes. A light coat of dark paint, as for example, a composition containing linseed oil, turpentine, and brown burnt 60 umber will then be applied to the coated surface of the shade, and immediately wiped, 65 leaving only a very thin coat remaining on the surface so as not to interfere with the translucence or light-penetrating qualities of the shade. After permitting the dark paint "wiped" coat to dry for a period of from 70 four to five hours, the inner coated surface of the shade will next be manually scraped or burnished by means of a squared-edged metal implement, in order to enhance the crackled or leather effect and produce a dull 75 non-shiny appearance.

The final step is to apply a finishing coat of plasticizing lacquer and castor oil on both sides of the silk fabric of the shade in order 80 to render the fabric pliable and to prevent the inside crackle coat from peeling off. When this finishing coat has been allowed to dry three or four hours, the lampshade 85 will be complete.

While there has been disclosed in this 80 specification one example of how the invention may be embodied in practice, it will be understood that the invention is not to be limited to this specific example, but may be modified and embodied in various ways 85 without departing from its spirit. In short, the invention includes all the modifications and embodiments coming within the scope of the following claims.

Having thus fully described the invention, 90 what is claimed as new, and for which it is desired to secure Letters Patents, is:

1. The method of treating a lampshade fabric which comprises applying a foundation coat of lacquer to one side of said fabric, 95 allowing it to dry, applying a second coat of lacquer over said foundation coat, allowing it to dry, applying a coat of "crackle" lacquer over said second coat, allowing it to dry, applying a coat of dark linseed oil base paint 100

to said crackle coat, wiping immediately, drying, scraping said dark coat with a square-edged tool, and applying a final coat of lacquer to said scraped surface.

- 5 2. The method of treating a lampshade silk fabric which comprises applying a foundation coat of lacquer to one side of said fabric, allowing it to dry, applying a second coat of lacquer over said foundation coat, allowing it to dry, applying a coat of "crackle" lacquer over said second coat, allowing it to dry, applying a coat of dark linseed oil base paint to said crackle coat, wiping immediately, drying, scraping said dark coat with a square-edged tool, and applying a final coat of lacquer to said scraped surface.
- 10 3. The method of treating a lampshade fabric which comprises applying a foundation coat of lacquer to said fabric, allowing it to dry, applying a second coat of lacquer over said foundation coat, allowing it to dry, applying a coat of "crackle" lacquer over said second coat, allowing it to dry, applying a coat of dark linseed oil base paint to said crackle coat, wiping immediately, drying, scraping said dark coat with a square-edged tool, and applying a final coat of lacquer to said scraped surface.
- 15 4. The method of treating a lampshade fabric which comprises applying a foundation coat of lacquer to one side of said fabric, allowing it to dry, applying a second coat of lacquer over said foundation coat, allowing it to dry, applying a coat of "crackle" lacquer over said second coat, allowing it to dry, applying a coat of dark linseed oil base paint to said crackle coat, wiping immediately, drying, scraping said dark coat with a square-edged tool, and applying a final coat of lacquer to said scraped surface.

- 20 5. The method of treating a lampshade fabric which comprises applying a foundation coat of lacquer to one side of said fabric, allowing it to dry, applying a second coat of lacquer over said foundation coat, allowing it to dry, applying a coat of "crackle" lacquer over said second coat, allowing it to dry, applying a coat of dark linseed oil base paint to said crackle coat, wiping immediately, drying, scraping said dark coat with a square-edged tool, and applying a final coat of plasticized lacquer to both sides of said fabric.
- 25 6. The method of treating a lampshade fabric which comprises applying a foundation coat of lacquer to one side of said fabric, allowing it to dry, applying a second coat of lacquer over said foundation coat, allowing it to dry, applying a coat of "crackle" lacquer over said second coat, allowing it to dry, applying a coat of dark linseed oil base paint to said crackle coat, wiping immediately, drying, scraping said dark coat with a square-edged tool, and applying a final coat of plasticized lacquer to both sides of said fabric.

- 30 7. The method of treating a lampshade fabric which comprises coating said shade with quick-drying "crackle" lacquer, drying, applying a coat of linseed-oil paint, wiping immediately, drying, and scraping with a square-edged tool to produce a dull finish.

- 35 8. The method of treating a lampshade fabric which comprises coating said shade with quick-drying "crackle" lacquer, drying, applying a coat of linseed-oil paint containing burnt umber pigment, wiping immediately, drying, and scraping with a square-edged tool to produce a dull finish.

- 40 9. The method of treating a lampshade fabric which comprises coating said shade with quick-drying "crackle" lacquer, drying, applying a coat of linseed-oil paint, wiping immediately, drying, scraping with a square-edged tool to produce a dull finish, and applying a plasticized final coat of lacquer and castor oil to said scraped coated surface.

- 45 10. The method of treating a translucent sheet which comprises coating said translucent sheet with quick-drying "crackle" lac-

quer, drying, applying a coat of linseed-oil paint, wiping immediately, drying, and scraping with a square-edged tool to produce a dull finish.

50 11. The method of treating a translucent lampshade which comprises applying a foundation coat of plasticizing pyroxylin lacquer, coating it with "crackle" lacquer, applying a thin pigmentized coat of linseed-oil paint, and burnishing to produce a dull finish.

55 12. In a lampshade, a sheet of translucent silk fabric having an ornamental coating of lacquer on one side thereof, a thin scraped coating of dark linseed-oil paint over said lacquer, and a plasticized coating of lacquer and castor oil over said scraped coating.

60 13. The method of treating a lampshade fabric which comprises applying a foundation coat of lacquer to one side of said fabric, allowing it to dry, applying a second coat over said foundation coat, allowing it to dry, applying a coat of "crackle" lacquer over said second coat, allowing it to dry, applying a coat of paint to said "crackle" coat, wiping immediately, drying, and applying a final coat of plasticized lacquer to both sides of said fabric.

65 In testimony whereof, I have affixed my signature to this specification.

AARON KISS.
